UNITED STATES PATENT OFFICE.

FRANK B. COOK, OF CHICAGO, ILLINOIS, ASSIGNOR TO FRANK B. COOK COMPANY, OF CHICAGO, ILLINOIS, A CORPORATION OF ILLINOIS.

FUSE.

1,099,589.

Specification of Letters Patent.

Patented June 9, 1914.

Application filed May 10, 1911. Serial No. 626,385.

To all whom it may concern:

Be it known that I, FRANK B. COOK, a citizen of the United States, residing at Chicago, in the county of Cook and State of Illinois, have invented certain new and useful Improvements in Fuses, of which the following is a specification.

The object of this invention is to provide an improved fuse for electrical purposes.

10 In the accompanying drawings, Figure 1 is a side elevation of a fuse embodying the features of my invention. Figs. 2 to 5 are views, in a series, showing the manner of making the fuse. Fig. 6 is a view of one of 15 the strips which constitute the end caps of the fuse.

A fuse embodying my invention comprises an elongated sheet or strip 11 of mica or other suitable material, said sheet having 20 notches 12 in opposite side edges thereof, the two series of notches at the opposite edges being staggered with reference to each other. A fuse wire 13 is wrapped a suitable number of times around the sheet 11 and in 25 the notches 12, said notches serving as a gage to indicate the proper amount of wire to be wound upon the sheet 11, and also to space the wire from the edges of the sheet. After the wire 13 has been wound around the sheet 30 11, sheets 14 of mica or other suitable material are placed at opposite sides of the sheet 11, as shown in Fig. 4, the end portions of the fuse wire 13 preferably being bent around the ends of the sheets 14. The end 35 portions of the fuse wire lie upon the outer sides of the sheets 14. Strips 15 of conducting material, as copper, are now folded about the opposite ends of the sheets 11 and 14, and the whole secured together by dipping 40 the ends in solder or other suitable material, as indicated at 16 in Fig. 1. The strips 15 form the end caps of the fuse, said caps being at all times in electrical contact with the end portions of the wire 13. Being carried 45 to the extreme end of the fuse, and being in

extended contact with the metallic end caps, the wire is readily accessible to the solder, and is thus secured to the end caps in the operation of soldering together the folds of the end caps.

By the use of flat insulation, sheet insulation, which is usually the cheapest form, may be used; and from this the blanks may be cheaply and rapidly cut or punched. The flat shape requires less material and occupies less space for a given length than any other shape. The flat end-cap is cheaply attached, gives a form fitting many common fuse clips, and allows screw slots similar to those of many ordinary fuses to be easily 55 punched. The sharp bend in the notches instantly destroys the arc which tends to form when the fuse explodes, and by winding the wire around the strip a very short fuse for a given wire-length is obtained.

50 I claim as my invention:

In a fuse, in combination, an inner flat sheet of insulating material, two outer sheets of insulating material lying at opposite sides of said inner sheet, said inner sheet having 55 notches in its opposite edges, the notches in one edge being staggered with relation to those in the other edge, a fuse wire wrapped about said inner sheet and lying in the bottoms of said notches, the end portions of 60 said fuse wire being bent around the ends of said outer insulating sheets, the end portions of the fuse wire lying upon the outer sides of the outer insulating sheets, strips of 65 conducting material bent to inclose the ends of 70 said fuse wire and contacting the latter, and solder securing each inclosing strip to the adjacent end portion of the fuse wire.

In testimony whereof I affix my signature in presence of two witnesses.

FRANK B. COOK.
